DESIGN FOR A COMBINED DISPLAY FIXTURE AND BRUSH CONTAINER

Chester S. Plasket, Cleveland, Ohio, assignor to
The Bixler Corporation, Cleveland, Ohio

Application June 25, 1945, Serial No. 120,340

Term of patent 7 years

(Cl. D80—9)

To all whom it may concern:

Be it known that I, Chester S. Plasket, a citizen of the United States, residing at Cleveland, in the county of Cuyahoga and State of Ohio, have invented a certain new, original, and ornamental Design for a Combined Display Fixture and Brush Container, of which the following is a specification, reference being had to the accompanying drawing, forming a part thereof.

In the drawing:

Fig. 1 is a front-elevational view of a combined fixture and brush container showing my new design.

Fig. 2 is an end-elevational view thereof.

Fig. 3 is a top plan view.

What I claim is:

The ornamental design for a combined display fixture and brush container, as shown.
